FIG. 1 is a top perspective view of an aquarium underwater filter unit showing my new design.

FIG. 2 is a front elevational view thereof.

FIG. 3 is an end elevational view thereof looking from the left end of FIG. 1.

FIG. 4 is an end elevational view thereof looking from the right end thereof.

FIG. 5 is a bottom view thereof on a reduced scale.

FIG. 6 is an exploded top perspective view thereof on a normal scale showing the components of the filter unit in disassembled relation.

FIG. 7 is a top perspective view of the unit of FIG. 1 shown in relation to an interconnected similar unit.

The decorative ribs and the louvers are partially shown in FIGS. 5, 6 and 7 for convenience of illustration.

The broken lines representing a fragmentary portion of an aquarium, air and water pipes and an intercon-

nected similar unit in FIGURES 1, 6 and 7 are shown for illustrative purposes only.

I claim:

The ornamental design for an aquarium underwater filter unit, as shown and described.
